(57) **CLAIM**

The ornamental design for a children's portrait growth chart, as shown and described.

DESCRIPTION

FIG. 1 is a front elevation view of the children's portrait growth chart showing my design;

FIG. 2 is a rear elevation view thereof;

FIG. 3 is a right side elevation view thereof, the opposite being a mirror image;

FIG. 4 is a top plan view thereof;

FIG. 5 is a bottom plan view thereof; and,

FIG. 6 is a perspective view thereof.
